UNITED STATES PATENT OFFICE.

THEOPHILUS VAN KANNEL, OF NEW YORK, N. Y., ASSIGNOR TO VAN KANNEL REVOLVING DOOR COMPANY, OF NEW YORK, N. Y., A CORPORATION OF WEST VIRGINIA.

ROTATABLE PARTITION-SHELF.

No. 840,599.

Specification of Letters Patent.

Patented Jan. 8, 1907.

Application filed June 3, 1905. Serial No. 263,653.

To all whom it may concern:

Be it known that I, THEOPHILUS VAN KANNEL, a citizen of the United States, residing at 524 East One Hundred and Thirty-fourth street, New York, county of New York, and State of New York, have invented certain new and useful Improvements in Rotatable Partition-Shelves, fully described and represented in the following specification and the accompanying drawings, forming a part of the same.

This invention relates to a pantry-shelf rotatable in a partition between two rooms; and the object of the present invention is to render such a rotating pantry-shelf more impervious to the passage of hot air, fumes, gases, or odors, which object is attained by a special construction of the drum which contains the shelf and a special construction of the casing surrounding the drum and which is supplied with packings set ninety degrees apart in contact with the periphery and heads of the drum. The doorways in the drum are made less than ninety degrees in their opening, and the packings upon the casing are set ninety degrees apart, so as to always cover the doorways in their rotation from one side of the partition to the other, and the packings which fit the heads of the drum are extended across between the ends of the vertical packings, so as to frame the drum completely within a yielding packing, which absolutely prevents the passage of fumes.

To increase the utility of the device, a drum provided with a segmental shelf intermediate to the heads is formed with doorways in opposite sides of the drum above and below such intermediate shelf which permits articles to be placed upon or removed from the bottom shelf through a doorway on one side of the partition, while articles are placed upon or removed from the intermediate shelf through the doorway at the opposite side of the partition.

The drum should be provided with means to set it automatically (when turned) in a central position with the doorway in the opening of the casing, and the connections for turning the drum are arranged at both sides of the partition, so as to operate the same from either side.

The various features of construction are illustrated in the annexed drawings, in which—

Figure 1 is a cross-section on line 2 2 in Fig. 2. Fig. 2 is a front elevation of a partition provided with the pantry-window. Fig. 3 is a plan in section on line 3 3 in Fig. 1, showing the hand connections for turning the drum in Fig. 1. Fig. 4 is a section of the partition on line 4 4 in Fig. 2 with such part of the operating mechanism as is exposed thereby. Fig. 5 is a plan in section on line 5 5 in Fig. 1. Fig. 6 is a plan in section on line 6 6 in Fig. 1.

In Fig. 1 dotted lines F⁴ show the path of the drum sides when the drum is rotated.

In Figs. 1 to 6, inclusive, A designates the partition separating two rooms A' A², with which the pantry-window communicates. B designates a table attached to the partition upon one side, and C a journal in the partition near the table for the bottom head D of the drum. Such head is shown made of two plates connected by an intermediate ring D' and strips D², which form a more durable structure than a single plank for the lower head of the drum. The upper head E is circular like the lower head and rigidly connected therewith by quadrantals F, Fig. 6. An intermediate shelf G is attached to the sides F between the two heads, and a quadrant panel H is fitted between the intermediate shelf and the upper head at one edge of the shelf and a similar panel between the shelf and the lower head at the opposite edge of the shelf, leaving the space between the sides F open at opposite edges of the shelf above and below the same. The construction of the drum with quadrantals F and quadrantals fitted between the same, at opposite sides of the drum above and below the intermediate shelf, furnishes a cheap and effective construction for providing the drum with doorways upon opposite sides. Each of the panels H is provided with a window I to permit a person at either side of the structure to see the movements of a person upon the other side. A journal J is projected from the top of the drum through a bearing upon a frame K within the top L of the casing, which incloses the opening through the partition and which is projected from both

sides of the partition into the rooms A' and A². The casing has sides M, Figs. 5 and 6, carrying packings N ninety degrees apart in contact with the sides F of the drum. The 5 sides F embrace an arc of a little more than ninety degrees, so that one or other of the packings is always in contact with each of the sides and prevents any passage of smoke or fumes past such sides. Flexible packing- 10 flaps o² for the top head of the drum are shown in Fig. 1 arranged in straight lines between the ends of the packings N and in Fig. 5 arranged radially. The packings shown in Fig. 1 extend, like the packings o, between 15 the ends of the vertical packings N, and thus wholly inclose or frame in the drum between yielding surfaces which prevent smoke or fumes from entering the casing. Such a drum may be turned by pulling the structure 20 where it protrudes outside of the casing and also by gearing connected with a pulley upon the journal of the drum.

In Fig. 3 the drum is shown with a projecting lug P, and blocks Q are attached to 25 the sides M of the casing to arrest the drum when given a half-rotation.

A grooved pulley R is shown in Figs. 2 and 3 attached to the journal J, with a cord S wrapped around the same and its ends extended over guide-wheels T and attached to 30 a pulley U, mounted upon a crank-shaft V, extended through the partition A. The partition is shown in Figs. 3 to 6, like most permanent partitions in large buildings, made 35 with central joists and sheathing upon both sides. This leaves a hollow space in which the drum U can be located and the guide-pulleys T pivoted at the level of the pulley R. The cord S can then be extended from the 40 casing within the partition, as shown in Fig. 3, and the connections for operating the drum be almost entirely concealed. The shaft has hand-cranks W upon opposite sides of the partition, and the ends of the 45 cord are wrapped in separate spiral grooves on the pulley. The cranks W stand normally in the lowest position. The pulley U is made of such size that a rotation of the crank-shaft gives the drum a half-rotation. 50 Where stops, like P Q in Fig. 3 are used, the hand-crank and drum would be turned alternately in opposite directions; but a cam 55 may be provided to set the drum automatically in either of its two opposite positions and the drum turned always in the same direction. Such a cam a is shown in Fig. 5 formed as a part of the journal J, the cam having two rounded ears projected laterally from opposite sides of the journal, with re- 60 cesses a' upon opposite sides between the same, adapted to fit rollers b, which are pivoted upon opposed leaf-springs c. These springs are supported at the ends by studs upon the top of the casing and are pressed 65 apart by the ears of the cam as the drum is

rotated, and their reaction when the drum is brought nearly to its desired position forces the rolls into the recesses and sets the drum in the desired position.

The side packings for the drum could be 70 attached to the sides F if the casing were made concentric therewith; but such a casing would be unnecessarily expensive, and the introduction of the drum to the casing is greatly facilitated by making the sides M 75 of the casing parallel, as shown in Fig. 6, with guide-bars M' projected from the edges toward the drum to carry the packings N.

The word "quadrantal" has been used herein for describing the sides F of the drum, 80 as well as the panels H intermediate to the same, and such parts may have an arc a little more or less than ninety degrees, according to the function they perform. The outer side of the panel H is necessarily (where exposed) less than ninety degrees in its arc if the sides F are made greater than such arc, as is desirable to maintain their contact with the packings N.

The casing is shown in Figs. 1, 5, and 6 90 projected at both sides of the partition, and the portion above the top of the drum formed with a swell front H', corresponding in curve with the sides of the drum, and such shape affords a desirable architectural finish 95 to the structure and furnishes a complete support for the packings to prevent the passage of fumes and smoke through the casing. In practice the part H' is made removable to permit the insertion of the drum in the cas- 100 ing.

The packings O, attached to the bottom of the casing, are transverse to the opening through the casing, although they are parallel with the partition and are preferably 105 clamped upon a slotted strip O', held by screws p', so that the packing can be adjusted toward the head of the drum as the packing wears.

Having thus set forth the nature of the invention, what is claimed herein is—

1. The combination, with a partition separating two rooms and extended from the floor to the ceiling and having a passage therethrough, of a suitable casing attached 115 to the edges of such passage-way and projected from opposite sides of the partition, a cylindrical drum having a segmental doorway of less than ninety degrees and heads at the top and bottom with journals fitted to 120 turn in the casing, the casing inclosing at least one-quarter of the periphery upon two opposite sides of the drum, with quadrantal openings at opposite sides of the casing adapted to communicate with either of the 125 doorways of the drum, and two rectangular frames of packings attached to the edges of the casing around such quadrantal openings at the opposite sides of the casing, such packings bearing upon the periphery of the drum 130

and upon its upper and lower heads, whereby the passage of air through the casing is prevented in all positions of the drum.

2. A duplex rotatable delivery-shelf having a drum with two heads, an intermediate shelf, and quadrantal doorways in the drum at opposite sides above and below the intermediate shelf, a casing inclosing at least one-quarter of the periphery upon each of two opposite sides of the drum, with quadrantal openings at opposite sides of the casing adapted to communicate with either of the doorways of the drum, and packings attached to the casing about ninety degrees apart, to bear upon the periphery of the drum and prevent the passage of air past its sides.

3. A rotatable delivery-shelf, comprising a drum having two heads D and E and an intermediate shelf G connected by opposite quadrantal sides F with intermediate openings of less than ninety degrees, quadrantal panels H closing the openings upon opposite sides of the drum above and below the intermediate shelf, a casing M embracing opposite quadrants of the drum, journals upon the drum fitted to the casing, and vertical packings attached to the casing at least ninety degrees apart to bear upon the sides of the drum.

4. A rotatable delivery-shelf comprising a drum having a quadrantal doorway, a casing inclosing opposite quadrants of the drum with opposite openings corresponding to such doorway, and supporting-journals upon the drum, a cam rotatable with the drum and provided with two opposite recesses, and a yielding member upon the casing having a projection to fit the said recesses and adjusted to permit the rotation of the drum in either direction, and to automatically set the drum, when released from the rotary force, with its doorways opposite to the openings in the casing.

45 5. A rotatable delivery-shelf comprising a drum having a quadrantal doorway, a casing inclosing opposite quadrants of the drum, with opposite openings corresponding to such doorway, and supporting-journals upon the drum, a cam a rotatable with the drum and having two projections with intermediate recesses a', the opposed leaf-springs c with rollers b fitted to the said recesses and supported

upon the casing by studs, the rolls permitting the drum to rotate in either direction and adjusted to automatically set the drum when released from the rotary force, with its doorways opposite the openings of the casing.

6. The combination, with a hollow partition having a passage-way extended therethrough, of a drum journaled in the passage-way and having a quadrantal doorway, the casing M applied to the edges of the passage-way and embracing opposite quadrants of the drum's periphery, the pulley R attached to one of the journals of the drum, the crank-shaft V extended through the partition with hand-cranks W at opposite sides of the partition and pulley U mounted thereon inside the partition, and a cord S running over the pulley P and extending from the opposite sides thereof out from the casing and within the partition, and its ends wound about the pulley U in opposite directions, whereby the connections for rotating the drum are concealed in the partition and casing.

7. The combination, with the hollow partition A having a passage-way extended therethrough, of the drum E mounted in the passage-way and having a quadrantal doorway, the casing M applied to the edges of the passage-way and embracing opposite quadrants of the drum's periphery, the journals C and J upon the drum fitted to the casing, the pulley R attached to the journal J, the crank-shaft V extended through the partition with hand-cranks W at opposite sides of the partition and pulley U mounted thereon inside the partition, said pulley being one-half the size of the pulley R, guide-pulleys T within the partition at the level of the pulley R and above the pulley V, and a cord S running over the pulley E and extended from the opposite sides thereof out from the casing and within the partition over the guide-pulleys T and its ends wound around the pulley U in opposite directions, whereby a complete revolution of either crank turns the drum one-half a rotation in its casing.

In testimony whereof I have hereunto set my hand in the presence of two subscribing witnesses.

THEOPHILUS VAN KANNEL.
